MACHINE FOR COILING METAL STRIP

Michel Nigro, Worcester, Mass., assignor to
 Sleeper & Hartley, Inc., Worcester, Mass., a
 corporation of Massachusetts

Application May 6, 1932, Serial No. 609,700

14 Claims. (Cl. 153—64.5)

The present invention relates to the coiling of metal strip, on edge, for the purpose of producing helical forms of varying pitch and diameter. The invention contemplates the provision of instrumentalities particularly adapted for producing helical forms closely encircling a supporting member, or core, with the convolutions of the helix uniformly spaced and with the wound strip providing corrugations closely engaging the core.

10 As will hereinafter appear, a helical form produced by practice of the invention is particularly suited for use in connection with the radiation of heat from a rod or a pipe, around which the form is coiled. Due to the uniform spacing of 15 the convolutions of the coil and the provision of corrugations, or fins, in the strip closely engaging the supporting rod or pipe, a maximum heat radiating effect is obtained, thereby adapting the product of the invention for use in heating or 20 refrigerating installations, or for other analogous purposes.

In carrying out the coiling operation, crimped strip is fed on edge, at a predetermined rate, to coiling tools rotatable about the coiling axis, and 25 as the strip is wound, the outer edge thereof is flattened. The increase in length of one edge of the strip, resulting from the flattening, not only assists in the coiling action, but also causes the crimping along the other edge, on the inside of 30 the coil, to draw together and very closely engage a rod or pipe on which the helix is being wound.

Other and further objects and advantages of the invention will appear from the following detailed description, taken in connection with the 35 accompanying drawings, in which:—

Fig. 1 is a front elevation of a machine embodying the invention.

Fig. 2 is a side elevation of the machine of Fig. 1.

40 Fig. 3 is a fragmentary section through the flier substantially along the line 3—3 of Fig. 1.

Fig. 4 is a plan view showing the drive for the machine, parts being broken away.

Fig. 5 is an enlarged fragmentary section 45 through the coiling rolls.

Fig. 6 is a horizontal section substantially along the line 6—6 of Fig. 1.

Fig. 7 is a perspective view of a coil formed by the machine.

50 Like reference characters refer to like parts throughout the drawings.

Referring to Figs. 1 and 3, the machine comprises a base 1 having spaced upwardly extending portions 2 in which a hollow sleeve 3 is rotatably supported by anti-friction bearings 4. The sleeve

3 is provided at its forward end with a radial flange 5 on which the flier, indicated generally at 6, Fig. 2, is mounted and said sleeve has secured thereto between the upstanding portions 2 a sprocket 7 by which the sleeve 3 is rotated as will hereinafter appear.

The flier 6, Fig. 3, comprises members 8 and 10, the former of which is secured to the radial flange 5 of the sleeve 3 by screws 11 and said members are suitably secured together for rotation, as a unit, with the drive for the mechanism which feeds the strip material *a* mounted in an opening 9 between said members. The strip material *a* is carried on a reel 12 supported on guide rolls, not shown, mounted on the flier 15 to permit rotation of said reel relative to the flier and the strip material is drawn from said reel 12 over guide rolls 13, carried on brackets 14 secured to the flier, by a feeding and forming mechanism 15 carried on the flier. 20

The feeding and forming mechanism turns the strip material *a* into a plane perpendicular to the axis of the coil and forms uniform transverse corrugations in the strip. This mechanism 15, which is best shown in Fig. 6, comprises a 25 pair of guide rolls 16 mounted on parallel axes perpendicular to the axis of the flier, said rolls 16 twisting the strip material *a* as it passes between said rolls from the guide roll 13 into a plane perpendicular to the axis of the flier. From 30 the guide rolls, the strip material passes between a pair of crimping and feeding rolls 17, the peripheries of which rolls are corrugated for crimping said strip, said rolls being driven in timed relation to the rotation of the flier to procure a positive feeding movement of the strip material as the flier rotates.

Referring now to Fig. 3, the sleeve 3 has a hollow sleeve 18 extending therethrough, said sleeve 18 being mounted for rotation within the sleeve 3 with the forward end of the sleeve 18 supported by an anti-friction bearing member 19, the outer race of which is mounted in the member 8 and with the rearward end of said sleeve 18 journaled in a bracket 20 carried by one of the 45 upstanding portions 2. A spur gear 21 is secured to the sleeve 18 between the members 8 and 10 and meshes with a spur gear 22, Fig. 1, journaled on a stud 23 carried by said members. The gear 22 meshes with an idler gear 24 journaled on a stud 25, said idler gear being in engagement with a pinion gear 26 secured to a shaft 27 journaled in the member 10. A bevel gear 28 is secured to the forward end of the shaft 27 and meshes with a bevel gear 30 secured to 50

the lower end of a shaft 31 to the upper end of which one of the crimping rolls 17 is secured; see Fig. 6. Rotation of the crimping rolls 17 is thus procured in response to rotation of the sleeve 18 5 relative to the flier.

As above stated, the rolls 17 are driven in timed relation to the flier and this timed relation is variable to procure a faster or slower speed as desired. To this end, the sleeve 3 which carries the 10 flier has a sprocket 32, Figs. 2 and 3, secured to the rearward end thereof, and said sprocket is connected by a chain 33 to a sprocket 34 of a reduction gear set 35 of the usual construction. The driven sprocket 36 of said reduction gear 15 set 35 engages a chain 37 which passes over a sprocket 38 secured to the rearward end of the sleeve 18. The reduction gear set 35 is adjustable to procure various speed ratios between the sprockets 34 and 36, thereby to vary the relative 20 rates of rotation of the sleeve 3 and the sleeve 18. Thus the rate of movement of the strip material *a* between the rolls 17 may be varied by adjustment of said gear set 35 with said feed rolls 17 driven in timed relation to the sleeve 3.

25 Referring now to Fig. 3, a sleeve 40 is mounted within the sleeves 3 and 18 and is supported therein at the forward end by anti-friction bearings 41 between said sleeve 40 and the member 10. The rearward end of said sleeve is mounted 30 in the bracket 20 and secured against rotation therein by a key 42. An arbor 43 which is mounted in the forward end of said sleeve has an axial opening therethrough for the reception of a coiling core or pipe 44 which is fed through 35 said arbor and upon which the strip material *a* is coiled as it is fed by the rolls 17, with coiling rolls 45 and 46 cooperating with said arbor in forming the strip into a helical coil about said pipe.

40 The coiling roll 45 is driven in timed relation to the flier and operates to iron out the crimps or corrugations in the outer periphery of the helix to form the structure of Fig. 7 which will be hereinafter more completely described. Referring to 45 Fig. 3, the coiling roll 45 is carried by a bracket 47 mounted on the face of the flier member 10, said bracket having a shaft 48 journaled in anti-friction bearings 50 parallel to the axis of the flier to which said roll is secured. A pinion 51 is also 50 secured against rotation on said shaft and engages with pinion teeth 52 formed on the periphery of the arbor 43. A thrust bearing 53 supports the shaft 48 against endwise movement resulting from the action of clamping the strip material *a* between 55 a shoulder 54 on the roll 45, and a corresponding shoulder 55 on the arbor 43, see Fig. 5. An adjusting nut 53a cooperating with the bearing 53 determines the position of the roll 45 with respect to arbor 43, and as the flier rotates, pressure 60 between the opposed shoulders 54 and 55 flattens the strip around the outer periphery of the coil being formed. The nut 53a permits the pressure exerted by the roll 45 to be varied in order to obtain the desired degree of flattening. Radial 65 adjustment of the roll 45 is obtained by means of a screw 56 in threaded engagement with the bracket 47, the screw being turnable in a lug 56a provided by the flier portion 10.

The coiling roll 46 is arranged for free rotation 70 and for holding the flattened periphery of the strip *a* against the shoulder 55 on the arbor in the formation of the helix. The roll 46 is journaled on anti-friction bearings 57 and is carried by a bracket 58 which is adjustable radially relative 75 to the axis of the flier by an adjusting screw 59

to permit the formation of coils of varying diameters.

The opposite sides of the coiling rolls 45 and 46 adjacent the periphery converge to form a tapering edge on said rolls which extends between adjacent coils of the helix as it is formed on the core and the forward end of the arbor 43 is undercut as indicated at 60. Therefore, the spacing between the side faces of the rolls 45 and 46 and the end of the arbor 43 is great enough to accommodate the crimps in the strip material and to define the depth of said crimps which become substantially deeper adjacent the inner portion of the helix during the formation of the coil. Since the diameter of the arbor in the portion where 15 the gear teeth 52 are formed corresponds to the diameter of the outer periphery of the coil being formed, the coiling roll 45 procures an ironing or rolling action on the periphery of said helix which 20 procures the desired flattening effect without excessive frictional engagement between the coil being formed and the coiling roll. Varying diameters of coil may be accommodated by radial adjustment of the coiling rolls 45 and 46 and by an increase or decrease in the size of the arbor 43 25 by substitution of an arbor of the desired size, the annular shoulder 55 on the arbor corresponding in diameter to the outside diameter of the coil being formed. Obviously the diameter of the pinion gear teeth 52 on the periphery of the arbor 30 43 corresponds to the diameter of the annular shoulder.

As above pointed out, the pipe or core 44 on which the coil is formed is moved in timed relation to the rotation of the flier. Referring to 35 Fig. 4, the motor 61 carries a pinion 62 in mesh with a loose gear 63 on a drive shaft 64, the shaft carrying a sprocket 65 connected to the sprocket 7 on the sleeve 3 by a chain 66 to procure rotation of the flier. A sleeve 67 carrying the gear 63 is 40 adapted to be connected to the shaft 64 by a clutch mechanism 68 of any suitable construction and the shaft 64 carries a worm, not shown, which meshes with a worm gear 69 on a shaft 70. A gear 71 which is also secured to the shaft 70 meshes 45 with a gear 72 on a countershaft 73, the latter carrying a gear 74 meshing with a gear 75 secured to the rearward end of a shaft 76 journaled in a housing 77 which carries the core feeding rolls. The forward end of the shaft 76 carries the lower 50 core feeding roll 78, Fig. 2 and has secured thereto a pinion, not shown, which meshes with a gear 80 on a shaft 81 also journaled in the housing 77. The forward end of the shaft 81 carries the upper feeding roll 82, the latter being adjustable 55 vertically by a hand wheel 83 to procure a more or less positive clamping engagement between said rolls 78 and 82 to provide for a positive feeding movement of the core therebetween. Since the rotation of the rolls 78 and 82 is positively 60 procured from the same shaft 64 which drives the flier and the associated mechanism, the core 44 is fed in timed relation to the rotation of the flier 6.

The helical form produced by operation of the 65 above described mechanism is shown in Fig. 7, in which the pipe 44 has a helical coil 84 wound thereon with elements of said coil substantially perpendicular to the axis of the pipe. The coil 70 is provided with corrugations or crimps 85 which are of substantial depth adjacent the inner periphery of said coil and which gradually diminish toward the outer periphery 86 which is substantially flat. It will be noted that successive coils 75

of the helix are uniformly spaced apart on the core.

In the operation of the machine, the strip material which is carried on the reel 12 is drawn 5 therefrom over the rolls 13 by rotation of the crimping rolls 17 in response to rotation of the sleeve 18 which in turn is driven by rotation of the sleeve 3. The crimping rolls 17 form corrugations in the strip material *a* and feed it at a pre- 10 determined rate between the coiling roll 45 and the arbor 43 which cooperate, as above pointed out, to iron out the corrugations in the outer edge of said strip, thereby lengthening said edge and causing the strip to coil around the pipe, this coiling 15 action being aided somewhat by the axial surface 87 formed by the shoulder 54. As the flier continues to rotate, the coiling roll 46 engages the strip material *a* and aids in the formation of the coil, said roll also maintaining consecutive coils 20 spaced apart, as shown in Fig. 5. As the feeding action of the rolls 17 is adjustable, as above pointed out, the length of strip material fed for each rotation of the flier may be accurately determined so that the strip material is coiled on the 25 pipe sufficiently tight to prevent subsequent shifting of the coils axially of said pipe. Furthermore, the elongation of the outer edge of the strip due to the flattening causes the crimps 85 to be forced together to closely embrace the pipe. During the 30 formation of the coils on the pipe, the latter is fed in predetermined timed relation to the rotation of the flier and accordingly determines the pitch of the helix since the core 44 is fed forwardly a predetermined distance for each rotation of the 35 flier.

In order to support the forward end of the core against vibratory movements as a result of the coiling action, said end is carried by a horizontally movable carriage 88 which is movable on a horizontal guideway 90 supported by a stand 91, the 40 core being supported in a clamp 92 on the carriage. As the core is fed and the strip coiled thereon, the carriage moves away from the machine.

From the foregoing, it will be apparent that by 45 the present invention there is provided an improved method and machine for coiling helical forms from crimped metallic strip.

I claim,

1. In a machine of the class described, the combination with a rotatable flier for carrying a supply of strip material, and strip feeding and crimping means carried by said flier, of a positively driven coiling roll on said flier arranged to flatten out the corrugations along one edge of said strip. 50

2. In a machine of the class described, the combination with a rotatable flier for carrying a supply of strip material, and strip feeding and crimping means carried by said flier, of a coiling roll driven in timed relation to the flier, said roll operating to flatten out the corrugations in one edge of said strip. 55

3. In a machine of the class described, the combination with a rotatable flier for carrying a supply of strip material, and strip feeding and crimping means carried by said flier, of a coiling roll driven in timed relation to the flier, said roll operating to flatten out the corrugations in one edge of said strip, and means for controlling the degree of flattening of the flattening of said strip by said roll. 60

4. In a machine for coiling strip material on a core, the combination with a rotatable flier for carrying a supply of strip material, of strip feeding and crimping rolls carried by said flier and driven in timed relation thereto and positively 65 driven coiling means carried by said flier

and operating to flatten out the crimps in one edge of the strip for forming said strip into a coil with crimps in said strip extending at right angles to the axis of the core.

5. In a machine for coiling strip material on a core, the combination with a rotatable flier for carrying a supply of strip material, of strip feeding and crimping rolls carried by said flier and driven in timed relation thereto and positively driven coiling means carried by said flier for 10 forming said strip into a coil with crimps in said strip extending at right angles to the axis of the core, and means for feeding the core in timed relation to the rotation of the flier. 15

6. In a machine of the class described, the combination with a rotatable flier for carrying a supply of strip material and strip crimping means carried by said flier, of a positively driven coiling roll on said flier operating to flatten out the corrugations in one edge of said strip. 20

7. In a machine of the class described, the combination with a rotatable flier for carrying a supply of strip material, and strip crimping means carried by said flier, of a coiling roll driven in timed relation to the flier and operating to flatten 25 out the corrugations in one edge of said strip.

8. In a machine of the class described, the combination with a rotatable flier for carrying a supply of strip material, and strip crimping means carried by said flier, of positively driven means on 30 the flier for flattening out the corrugations in one edge only of said strip.

9. In a machine of the class described, the combination with a rotatable flier for carrying a supply of strip material, and strip crimping means carried by said flier, of a coiling roll driven in 35 timed relation to the flier and operating to flatten out the corrugations in one edge of said strip, and means for controlling the degree of flattening of said strip by said roll. 40

10. In a machine for coiling strip material, the combination with a rotatable flier for carrying a supply of strip material, of strip feeding and crimping rolls carried by said flier and driven in timed relation thereto and positively driven coiling means carried by said flier and operating to flatten out the crimps in one edge of the strip for forming said strip into a coil with the crimps therein extending at right angles to the axis of the coil. 45

11. In a machine of the class described, the combination with a rotatable flier for carrying a supply of strip material, a tubular guide extending axially through said flier, means for feeding a tube through said guide and means for driving said flier, of a coiling roll rotatably mounted on said flier with its periphery overlapping the adjacent end of said guide, and means carried by the flier to positively feed, for each revolution of the flier, a predetermined length of strip material 50 between opposed surfaces of said coiling roll and of said guide to wind the strip in spiral form on said tube. 55

12. In a machine of the class described, the combination with a rotatable flier for carrying a supply of strip material, a tubular guide extending axially through said flier, means for feeding a tube through said guide and means for driving said flier, of a coiling roll carried by said flier with its periphery overlapping the adjacent end 60 of said guide, means for rotatably driving said coiling roll from said flier, a pair of feeding rolls mounted on said flier, and means for variably driving said feeding rolls in unison with said flier 65 to cause said rolls to positively feed, for each 70

- revolution of the flier, a predetermined length of strip between opposed surfaces of said coiling roll and of said guide.
13. In a machine of the class described, the combination with a rotatable flier for carrying a supply of strip material, a tubular guide extending axially through said flier, means for feeding a tube through said guide and means for driving said flier, of a coiling roll carried by said flier 10 with its periphery overlapping the adjacent end of said guide, means for rotatably driving said coiling roll from said flier, a pair of corrugated rolls rotatably mounted on said flier, and means for driving said rolls in timed relation with said 15 flier for causing said rolls to crimp the strip material and positively feed, for each revolution of the flier, a predetermined length of crimped strip between opposed faces of said coiling roll and said guide.
14. In a machine of the class described, the combination with a rotatable flier for carrying a supply of strip material, a tubular guide extending axially through said flier, means for feeding a tube through said guide and means for driving said flier, of a coiling roll carried by said flier with its periphery overlapping the adjacent end of said guide, means for rotatably driving said coiling roll from said flier, a pair of corrugated rolls rotatably mounted on said flier, and means 10 for driving said rolls in timed relation with said flier for causing said rolls to crimp the strip material and positively feed, for each revolution of the flier, a predetermined length of crimped strip between opposed faces of said coiling roll and 15 said guide to wind the strip in spiral form on said tube, with its outer edge flattened by passage between said coiling roll and guide.

MICHEL NIGRO.
